UNITED STATES PATENT OFFICE

2,473,180

SMOKING PIPE CLEANER

Alfred L. Sohm, Van Nuys, Calif.

Application August 26, 1947, Serial No. 770,723

6 Claims. (Cl. 131—246)

1

My invention relates to improvements in pipe bowl cleaners or reamers and has for its principal object, to provide a device which is simple in structure, inexpensive of manufacture, and which may be conveniently used for the rapid and effective cleaning of the incrustations or deposits which accumulate on the inner face of the pipe bowl.

Further objects of my invention are, to provide a pipe bowl cleaner of the character referred to, which is readily adjustable in order that it may be used for cleaning the interior of pipe bowls of different sizes, and further, to provide the cleaner with a pair of fingerlike blades having sharp scraping and cutting edges disposed so that they may be simultaneously sharpened with a file or grinding wheel, or upon a flat faced hone.

With the foregoing and other objects in view, my invention consists in certain novel features of construction and arrangement of parts which will be hereinafter more fully described and claimed and illustrated in the accompanying drawings, in which:

Fig. 1 is a front elevational view of the pipe cleaner.

Fig. 2 is an enlarged vertical section taken on the line 2—2 of Fig. 1.

Fig. 3 is a fragmentary vertical section taken on the line 3—3 of Fig. 2.

Fig. 4 is a horizontal section taken on the line 4—4 of Fig. 1.

Fig. 5 is a horizontal section taken on the line 5—5 of Fig. 1.

Fig. 6 is a horizontal section taken on the line 6—6 of Fig. 1.

Fig. 7 is a horizontal section taken on the line 7—7 of Fig. 1.

Referring by numerals to the accompanying drawing, which illustrates a preferred embodiment of my invention, 10 designates a short tubular member within which are positioned the upper portions 11 of bowl scraping or reaming fingers 12, each of which is pressed or stamped from suitable metal and is substantially arcuate of channel shape in cross section.

The upper portions of members 11 are disposed within tubular member 10 and passing diametrically through the latter and through the upper positions of said body members is a pin 13, which carries between members 11 an expansion coil spring 14.

The ends of pin 13 project short distances outwardly from member 10, thus forming a cross handle for the convenient rotation of the cleaner during bowl cleaning operations.

2

Seated in the wall of member 10 below and in vertical alignment with pin 13, are the heads of short pins or studs 15, which project through apertures 16 in members 11, thus providing bearings between the lower portion of member 10 and the scraping fingers, as same are adjusted for use in different sized pipe bowls.

As seen in Figs. 3 and 5, both ends of the apertures 16 in members 11 are slightly reamed or countersunk in order to provide a slightly loose bearing between member 10 and members 11, and, therefore, prevent binding between the parts as said members 11 rock on their bearings on said member 10.

15 Loosely seated in short vertically disposed slots 17, formed in members 11 below tubular member 10 and in vertical alignment with pin 13 and studs 15, are the wedge shaped ends 18 of studs 19, having right and left hand threads respectively and these studs are seated in the correspondingly threaded ends of an axial bore 19, formed in a disc 20, having a milled edge.

20 Opposite portions of the periphery of this disc project outwardly slight distances beyond the vertical edges of members 11 just below member 10.

25 The edges of fingers 12 on one side are gradually curved toward their lower ends and the terminal portions 21 at said lower ends are shaped so as to generally conform to the shape of the lower portion of the chamber in the pipe bowl.

30 These curved edges of fingers 12 and portions 21 are formed with outwardly presented sharp edges 22 and flat faces 23, which latter occupy the same plane in order that a hone, file, or other abrasive tool may be conveniently used in sharpening said edges.

35 It is essential that the outer ends 18 of studs 19, rock slightly in the apertures 17 in order to accommodate the slight change in angularity of members 11 and fingers 12, as same move toward or away from each other when disc 20 is rotated.

40 Expansion spring 14 exerts pressure on the upper portions of members 11, thus tending to swing those portions of said members below member 10 and studs 15 toward each other.

45 To adjust the working width of the lower ends of fingers 12 for use in cleaning the recesses or pockets in different sized pipe bowls, disc 20 is rotated so as to swing members 11 upon their fulcrums 15 and thereby move the lower portions of fingers 12 toward or away from each other.

50 As disc 20 is rotated to move studs 19 apart, the lower ends of fingers 12 will be spread apart and the upper portions of members 11 will move to-

ward each other to compress spring 14 and these movements will be reversed when disc 20 is rotated to draw studs 19 toward each other, the expansive forces of spring 14 will act to move the upper ends of fingers 11 apart.

To clean the recess in a pipe bowl, the portions 12 are inserted in said recess, and by using pin 13 as a handle, the tool is rotated first in one direction and then in the other so that sharp edges 22 cut, scrape and thereby loosen the incrustations on the inner face of the wall of the bowl and by bearing down on the tool, the sharp edges of the lower end portions 21 of the fingers cut and loosen the crust or accumulation generally referred to as the "heel" in the bottom of the bowl.

Thus it will be seen that I have provided a pipe bowl cleaner which is simple in structure, readily adjustable for use in bowl recesses of different sizes, capable of being easily and quickly sharpened and very effective in performing the functions for which it is intended.

Minor changes in the size, form and construction of the various parts of my improved pipe cleaner may be made and substituted for those herein shown and described, without departing from the spirit of the invention, the scope of which is set forth in the appended claims.

I claim as my invention:

1. In a pipe cleaner, a tubular body member, a pair of oppositely disposed channel members having their upper end portions fulcrumed within said body member, a pin passing through said body member and the upper portions of said channel members, an expansion spring on said pin between said channel members, means con-

nected to and disposed between said channel members for moving same upon their fulcrums, and tapered fingers depending from said channel members.

5. The pipe cleaner as set forth in claim 1, and which said fingers are provided with sharp vertical outer edges.

3. The pipe cleaner as set forth in claim 1 and which said fingers are each provided with a sharp 10 vertical outer edge and with a flat face adjacent said vertical edge.

4. The pipe cleaner as set forth in claim 1 and which said channel member moving means comprises threaded studs having their outer ends 15 loosely seated in said channel members and a disc nut seated on said threaded studs.

5. In a pipe cleaner, a tubular body member, a pair of opposed members having their upper portions fulcrumed in said body members, sharp 20 edged fingers depending from said opposed members, threaded studs having their outer ends seated in said opposed members, and a disc nut screw on said threaded studs.

6. A pipe cleaner as set forth in claim 5, with 25 an expansion spring disposed between the upper ends of said opposed members.

ALFRED L. SOHM.
